UNITED STATES PATENT OFFICE.

JACOB B. WISE, OF CLEVELAND, OHIO.

ROOFING COMPOSITION.

1,235,270.

Specification of Letters Patent. Patented July 31, 1917.

Application filed February 8, 1913, Serial No. 745,825. Renewed February 1, 1917. Serial No. 146,000.

To all whom it may concern:

Be it known that I, JACOB B. WISE, a citizen of the United States, and a resident of Cleveland, county of Cuyahoga, and 5 State of Ohio, have invented a new and useful Improvement in Roofing Compositions, of which the following is a specification, the principle of the invention being herein explained and the best mode in which I have 10 contemplated applying that principle, so as to distinguish it from other inventions.

The present invention, relating as indicated to an improved roofing composition, has more particular regard to the improvement of the bituminous compositions which are largely used for the purpose in question, being applied both to the laid roof, or to sheets of paper which are to be subsequently placed on the roof. The object of the invention is to provide a composition which may be manufactured at a much lower cost than the one at present in use, while it at the same time will give equally, if not more, satisfactory results. To the accomplishment of 25 these and related ends, the invention consists of the ingredients hereinafter fully described and particularly pointed out in the claims.

Such following description, together with the annexed drawing set forth in detail one 30 approved mode of carrying out my invention, such disclosed mode, however, constituting but one of various ways in which the principle of the invention may be used.

In said annexed drawing:—

35 Figure 1 shows a vertical section through a portion of a roof laid with my present improved composition; and Fig. 2 represents a horizontal section taken on an enlarged scale through the same on the plane indicated by 40 the line 2—2, Fig. 1.

My present improved composition is in effect a liquid coating composition of paste or semi-paste-like consistency, being designed for application to any smooth roofing 45 surface, such for example as would be provided by the ordinary boards or sheeting which forms the foundation of most roofs, the cracks or spaces between the boards being caulked or otherwise closed. Or the said 50 composition may be applied to ordinary tar paper, metal, or composition roofings which may have worn out, and in fact the latter will afford a very large field for the use of the present composition. The latter is thus 55 distinguished from composition roofings as at present known, consisting of sheets of a

tar or equivalent bituminous base mixed with wool-felt or like fibrous material; as also from ordinary tar which has occasionally been used as a coating material for such 60 composition or felt roofings. As compared with either such composition roofing or tar coating, the present composition will be materially cheaper, permitting of the use of a much heavier coating at the same, or a lower, 65 cost, than if any of such present composition is used.

A liquid coating composition has a number of advantages in contra-distinction to a composition that comes in the form of a 70 sheet, since in laying it, joints or seams are entirely avoided, and there is no occasion to perforate the layer with nails or like fastening devices as is necessary in attaching sheet roofing to the foundation or support 75 forming the roof proper.

In carrying out the present invention I employ a mixture of asphalt or tar and pine oil, or other equivalent bituminous compound, with or without asbestos admixed, 80 adding thereto a quantity of fine, flat fragments of hard material such as crushed oyster or clam shell, this material being thoroughly mixed with the other ingredients so as to be evenly distributed throughout the 85 mass. The fragments of shell, even where relatively finely ground, will retain their flat character, that is, they will be quite thin in one dimension, as will be readily understood.

90 My improved composition is spread upon the roof, or the strips of material to be subsequently laid on a roof, while in the liquid or plastic condition referred to. The spreading operation may be conveniently performed by means of a trowel or brush, the composition being painted or brushed over the surface involving a forcing of a certain amount of the coating along the surface when applied too thickly in any one spot. 100 By reason of the thin, flat character of the shells in my composition, it may be thus spread without rolling or dragging the same along the surface as is the case where stones of round character are used.

105 Accordingly, when the mixture thus prepared is spread on the roof, whether an old roof such as has been previously referred to or a new one, these particles of material will lie flat and occupy no more, and really 110 less, vertical space than the layer of tar, or equivalent compound replaced thereby in

the composition. The space filled, however, by such fragments of shell correspondingly diminishes the amount of the other materials required to cover a given area. By reason of 5 their flatness, such fragments, however, do not detract in the slightest from the continuity of the coat and at the same time they permanently retain a film of the tar or asphalt even on their upper faces so that it is 10 in effect a continuous sheet of tar, as before, that is placed on the roof. Moreover, the effect of admixing this fragmentary material is to decrease the tendency of the resulting composition to run when exposed to 15 relatively high temperature, as under a hot sun.

The amount of shell which may be used is partly a matter of selection, it having been found that as high as fifty per cent. of the 20 composition may consist thereof. Obviously, the shell being much cheaper than the other ingredients, even tar, it is possible by use of the same to very materially decrease the cost of the composition, while by actual 25 experiment it is found that the latter gives more satisfactory results than if the mixture consisted simply of the tar and pine oil, asphalt, or other compositions heretofore used.

The general construction and application 30 of my roofing composition will be readily seen from Figs. 1 and 2 taken in connection with the foregoing explanation. In Fig. 1 I show the blocks or boards 1 which comprise the roof proper upon which there 35 will be placed a coating of the composition already described, either directly or with the intervention of a layer of paper as previously explained, such composition consisting of a bituminous substance 2 in which 40 there is held a quantity of flat pieces 3 of some such material as shells, slate, or equivalent material. Thus, in Fig. 1 it will be noted that several layers of paper 4 are shown, the roofing composition being ap-

plied to the upper surface of such layers 45 of paper.

In finishing a roof constructed with my improved composition, a thin layer of the shell may be sifted or sprinkled over the surface of the laid composition and troweled 50 down. This gives a desirable, ornamental appearance to the job.

Other modes of applying the principle of my invention may be employed instead of the one explained, change being made as 55 regards the process herein disclosed, provided the ingredients stated by any of the following claims, or the equivalents of such stated ingredients be employed.

I therefore particularly point out and distinctly claim as my invention:—

1. A roofing composition including in addition to a bituminous base, a quantity of crushed shell thoroughly mixed with such base and evenly distributed throughout the 65 mass, the longest dimension of the majority of the pieces of shell being greater than the thickness of the usual coating of the composition when applied to a roof.

2. A roofing composition including a base 70 made up of tar and pine oil forming an initially plastic compound, and a quantity of fine, flat fragments of crushed shell thoroughly mixed with such base and evenly distributed throughout the mass, such composition being capable of being spread evenly and continuously over a surface, and such fragments assuming a position in which their flat sides are substantially parallel to the surface to which such composition is 80 applied.

Signed by me this 31st day of January, 1913.

JACOB B. WISE.
